UNITED STATES PATENT OFFICE

ROBERT H. PLASS, OF MONTCLAIR, NEW JERSEY, ASSIGNOR TO THE CHAPAL DONNER CORPORATION, OF NEWARK, NEW JERSEY, A CORPORATION OF NEW JERSEY

PELT-DEHAIRING MACHINE

Application filed January 8, 1930. Serial No. 419,227.

This invention relates to improvements in machines for removing hair or fur from animal skins or pelts.

This invention has for its principal object 5 to provide a novel pelt dehauling machine having means for feeding the pelts to the cutting mechanism and holding the same subject to the hair or fur severing operation of the cutting mechanism, together with a novel 10 pneumatic means cooperative with said feeding and holding means and cutting mechanism for rapidly removing severed hair or fur from the cutting point without waste, while at the same time assuring efficient separation 15 of the hair or fur from skin cuts or slivers.

Other objects of this invention, not at this time more particularly enumerated, will be understood from the following detailed description of the same.

An illustrative embodiment of this invention 20 is shown in the accompanying drawings, in which:

Fig. 1 is a side elevation, and

Fig. 2 is a plan or top view of the novel pelt 25 dehauling machine of this invention; Fig. 3 is an enlarged view, in vertical section, of parts adjacent to the cutting point of the machine; and Fig. 4 is a fragmentary plan view of portions of the pelt feeding and holding 30 means as related to the pneumatic means for removing or conveying away severed hair or fur.

Similar characters of reference are employed in all of the above-described views, to 35 indicate corresponding parts.

Referring to said drawings, the reference character 5 indicates a cutting cylinder or drum, the shaft 6 of which is journaled in and extends between bearing members 7 which are supported on the frame-work 8 of the machine. Suitably secured to the cutting cylinder or drum are a plurality of radial and preferably longitudinally oblique shear blades 9. Secured to the bearing members 7, 40 so as to extend over and enclose the upper forward part of the cutting cylinder or drum 5, is a bed-knife frame 10 to which is suitably secured, as by bolts 11, a stationary cutting blade or bed-knife 12. Said stationary cutting blade or bed-knife 12 is mounted with its

cutting edge downward, and is disposed substantially parallel to the axis of said cutting cylinder or drum 5, so that the shear blades 9, on rotation of said cylinder or drum, will pass upwardly relative to and in functional co-operation with the cutting edge of said stationary cutting blade or bed-knife.

Journaled in and extending between bearing portions 13 connected with the bed-knife frame 10, is a shaft 14 on which is fixed a feed-roller 15. Said feed-roller 15 lies in front of and parallels the cutting edge of said stationary cutting blade or bed-knife 12.

Connected with the frame-work 8, to project outwardly from the ends of the cutting mechanism, are fixed side plates 16. Mounted in and extending between said side plates 16 is a fulcrum shaft 17. Pivotaly mounted on said shaft 17, to lie side by side throughout the space between said side plates 16, are 70 a plurality of pelt supporting members 18, which together provide a feed table over which pelts may be fed to the cutting point of the machine. Each supporting member 18 terminates at its inner end in a curved guide portion 19 which underlies and is opposed to the under surface of the feed-roller 15. Each supporting member 18 is normally positioned, with its guide portion 19 slightly spaced from the surface of said feed-roller 15, by engagement of its tail portion with a stop-bar 20, the latter being supported by and extending between said side plates 16 so as to underlie the tail portions of said supporting members. Said supporting members 18 are yieldably 80 biased to the described normal positions by pull-springs 21 adapted to exert downwardly swinging tension on the tail portions thereof. Said supporting members 18 serve to support and guide a pelt, fed forward to the cutting point of the machine, to, under and into propelled engagement by said feed-roller 15.

Since, however, each supporting member 18 is individually yieldable, some one or more of the same will yield to the passage of burrs, 90 excrescences or the like occurring in the pelt at any given point, without disturbing the function of the remaining supporting members in pressing the belt into propelled engagement with said feed-roller 15, and conse- 95 100

quently such imperfections in the pelt will not interfere with or obstruct in any way the desired steady, uniform and smooth movement of the pelt to the cutting point of the machine.

The cutting machine or drum 5 may be operatively rotated by any suitable power transmission means, as, for example, by a drive pulley 22 over which runs a drive belt 23 driven from a suitable source of power.

The feed-roller 15 is suitably driven at relatively slow speed. Illustrative of one manner of and means for driving said feed-roller 15, I have shown a reduction gearing intermediate the shaft 6 of the cutting cylinder or drum 5 and the shaft 14 of the feed-roller. As shown, said reduction gearing comprises a pinion 24 connected and rotatable with said shaft 6. Said pinion 24 meshes with and drives a large gear wheel 25 having concentric thereto and rotatable therewith a reducing gear 26, which, in turn, meshes with and drives an idler gear 27. Said idler gear 27 meshes with and drives a transmission gear 28 fixed on the feed-roller shaft 14. It will be understood, however, that the described transmission is subject to wide variation, and that I do not limit myself to the use of the illustrative form of the same.

Aligned with and adjacent to the cutting point of the machine, is an air conduit or pneumatic conveyer pipe 29, the same having an upwardly projecting mouth portion 30 providing an intake opening 31 underlying the guide portions 19 of said supporting members 18, and corresponding in length to the width of the feed table formed by the latter parts. Said air conduit or pneumatic conveyer pipe 29 extends endwise from a side of the machine, and may be suitably connected with an air exhaust means (not shown) for creating an air suction current therein. The guide-portions 19 of the supporting members 18 are provided with slotted openings 32 providing passages communicating with the intake opening 31 of said air conduit or pneumatic conveyer pipe 29. In order to prevent disturbing air eddy currents, and to assure the movement of air at or near the cutting point of the machine directly into the intake opening 31 of the air conduit or pneumatic conveyer pipe 29, I provide flexible closure flanges 33 and 34, which may be made of any suitable material, such as rubber, leather, etc. Closure flange 33 is preferably secured to the outer face of the stationary blade or bed-knife 12, with its free margin bearing or riding on the upper surface of the feed-roller 15. Closure flange 34 is preferably secured to the outer face of the mouth portion 30 of said air conduit or pneumatic conveyer pipe 29, with its free margin bearing or riding on the undersides of said supporting members 18.

In practice, the cutting cylinder or drum 5

is enclosed. The enclosure is effected in part by the bed-knife frame 10 and in part by a rear hood member or housing 35, and in part by the inner face or side of the air conduit or pneumatic conveyer pipe 29, all whereby the cutting cylinder or drum 5 revolves in a chamber 36 open at its lower side to communicate with any suitable form and arrangement of drop well or conduit 37.

In the operation of the machine, the rotation of the cutting cylinder or drum 5, at its forward face and relative to the cutting point of the machine, is upward. The revolution of the shear blades 9 produces a centrifugal air current within the chamber 36 in the direction of motion of the cutting cylinder or drum. As slivers of hide or skin are cut from the pelt, while severing the hair or fur from the latter, the same are carried around the chamber 36 by the centrifugal air current, and discharged into the drop-well or conduit 37, and being relatively heavy will gravitate through the latter to a place of collection.

As the pelt moves beneath the feed-roller 15 and intermediate the same and the guide portions 19 of the supporting members 18, the fur or hair is turned to extend rearwardly, whereby, as a portion of the pelt or skin moves over the edge of the stationary blade or bed-knife 12 and into the path of an approaching shear blade 9, a sliver of the hide will be cut away, thereby severing adjacent hair or fur filaments close to the bases or roots thereof. By the air suction applied to the air conveyer or pneumatic conveyer pipe 29, an ingoing current of air is caused to flow through the slots or openings 32 provided in the guide portions 19 of the supporting members 18, and thence into the intake opening 31 of the mouth portion 30. This ingoing air current will quickly suck into the conveyer pipe the severed hair or fur filaments, so that the same may be immediately carried to a point of collection, with risk of waste or loss substantially eliminated.

It will be obvious from the above description that the present invention provides an exceedingly simple dehauling machine, having means to quickly and efficiently assure the collection of severed hair or fur filaments in such manner as to eliminate waste or loss thereof. Said latter means by reason of its pneumatic character, involving a considerable reduction in movable parts necessary to the machine structure, and consequently not only affording a machine functioning in an efficient manner, but one which is economical both to build and operate.

I am aware that many changes could be made in the above described general construction of dehauling machine as well as in the details of the structure thereof, without departing from the scope of this invention, and therefore it is intended that all matter

contained in the above description or shown in the accompanying drawings shall be interpreted as illustrative and not in a limiting sense.

5 I claim:—

1. In a machine of the kind described, a cutting mechanism, a rotatable pelt feed roller in front of said cutting mechanism, a series of independently yieldable pelt supporting fingers arranged side by side in substantially horizontal plane and having guide portions opposed to said feed-roller and extending to the cutting mechanism, and an air suction conveyer means having an intake mouth coextensive with and adjacent to cutting point of the machine so as to receive and carry away hair or fur filaments severed from a pelt, said guide portion being of less width than the main bodies of said fingers to provide openings therebetween giving access to said conveyer means intake mouth.
- 10 2. In a machine of the kind described, a rotatable cutting cylinder having radial shear-blades, a stationary downwardly directed cutting blade having a cutting edge at its lower margin, said cutting cylinder being rotatable in a direction adapted to carry its shear blades upwardly relative to and in contact with said stationary blade cutting edge, a rotatable pelt feed-roller, a series of pivoted independently yieldable pelt supporting fingers arranged side by side in laterally abutting relation and in horizontal plane and having guide portions underlying said feed-roller, and extending to said cutting blade, an air suction conveyer means having an air intake mouth in front of and substantially coextensive with said stationary blade cutting-edge and underlying said guide portions of said pelt supporting fingers, and said latter parts having slotted openings therethrough giving access to said conveyer means intake mouth.
- 15 3. In a machine of the kind described, a rotatable cutting cylinder having radial shear-blades, a stationary downwardly directed cutting blade having a cutting edge at its lower margin, said cutting cylinder being rotatable in a direction adapted to carry its shear blades upwardly relative to and in contact with said stationary blade cutting edge, a rotatable pelt feed-roller, a series of pivoted independently yieldable pelt supporting fingers arranged side by side in laterally abutting relation and in horizontal plane and having guide portions underlying said feed-roller and extending to said cutting blade, an air suction conveyer means having an air intake mouth in front of and substantially coextensive with said stationary blade cutting edge and underlying said guide portions of said pelt supporting fingers, said latter parts having slotted openings therethrough giving access to said conveyer means intake mouth, and flexible flange members re-

spectively intermediate said stationary cutting blade and the upper side of said feed roller and the outer side of said suction conveyer means and the underside of said supporting fingers.

In testimony that I claim the invention set forth above I have hereunto set my hand this 3rd day of January, 1930.
